UNITED STATES PATENT OFFICE.

JAMES EDWARD WILSON, OF LINTON, INDIANA.

TRACK BEND FOR SLIDE RAILS.

Application filed September 20, 1926. Serial No. 136,584.

This invention relates to track bends for slide rails.

The object is to provide a curved section of track which may be conveniently used in connection with the slide rails and holders shown and described in Patent Number 1,376,128, issued to me on April 26, 1921.

The track bend of the present invention is designed to be readily transported in non-assembled condition to any point within a mine where it may be out of the way when not in use, and when a point has been reached at the end of the permanent track where it is desired to cut or mine a communicating door or passageway between one runway and another adjacent and parallel runway, the invention may be brought in sections and placed in position at the ends of the said slide rails, and coupled together to prevent displacement, for the purpose of enabling the mine car to be run off the permanent track and onto the slide rails and thence onto the track bend so that the car may be brought into close proximity to the side wall of the runway and the mined coal, etc. readily shovelled therein to be carried away.

Another object is to provide an easily and cheaply made device of this character which is strong and durable and which may be quickly set in position and locked together with the minimum expenditure of labor and loss of time, the sections comprising the bend being constructed in a manner to allow of their being placed to enable the car to be headed either to the right hand or the left hand wall as desired.

A full and complete understanding of the invention may be obtained from a consideration of the following detailed description, taken in connection with the accompanying drawing forming a part of this specification; it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:—

Figure 1 is a plan view of the terminal portion of a permanent mine track having

the slide rails in position and showing the improved track bend connected to the latter.

Figure 2 is an enlarged transverse sectional view taken substantially on the line 2—2 of Figure 1.

Figure 3 is a similar view taken on the line 3—3 of Figure 1.

As fully disclosed in the aforesaid patent, it is the custom to lay the permanent rails 1 of the mine track in position as fast as the coal is mined at the end of the runway and space is provided therefor.

When the coal has been mined some distance away from the ends of the permanent rails, and the car, standing upon the latter, is too far from the end wall of the runway, to permit of the coal being readily shoveled thereinto, the slide rails of the said patent are then brought into use to rest upon the last permanent tie 2 and immediately against the inner faces of the permanent rails, as shown, the latter being suitably braced and secured by spikes 3 in the usual manner.

The slide rails 4 are laid on their sides with the ball or tread portions interfitting between the balls and base flanges of the permanent rails so that the same assume an angular position, and said slide rails are supported upon temporary, spaced ties 5 and secured to the last permanent tie 2 by means of spikes 6, as clearly shown in Figure 1 of the drawing, said spikes bearing against the bottoms of the flanges which are located at the inner sides of said rails.

When the wheels of the mine car (not shown) reach the end of the permanent rails 1 they drop off the same and onto the sides of the ball portions of the slide rails with the flanges of the wheels in the uppermost depressed portions of the slide rails, and said car may then be rolled along to the ends of the slide rails which are located adjacent to the end of the runway where the coal is to be mined, it being understood that the slide rails are moved or slid outwardly along the inner sides of the permanent track and upon the temporary ties 5, as the same are needed in an obvious manner.

When the runway has been bored or mined to a point where it is desired to cut or mine a door or passageway through the side wall, either at one side or the other, to form a communication between two parallel runways, it has been found advantageous to run the mine car up close to the face of the side wall to facilitate loading the same,

and that said car is too far away from the side wall when the same is standing upon the permanent tracks, and it is this feature that has brought about the present invention.

In places where the floor is soft, suitably spaced ties 7 are used, the same being placed in radial positions to approximate the curvature of the track bend and the arcuate rails 9 of the track bend are placed in position thereon. These rails 9 are laid upon their sides to accord exactly with the aforesaid slide rails, as clearly shown in Figures 2 and 3 of the drawing, the rails resting upon one edge of the base flange and upon the sides of the ball portions thereof, and with the said flanges in opposed relation to each other. The ties 7 may be dispensed with where the floor is hard enough to support the curved rails.

The rails 9 may be formed on any desired curve, the two rails being concentric and equally spaced apart throughout their lengths and intermediate between their ends are provided with ears 10 which are welded or otherwise secured to the inner faces of the base flanges. Crossed tie rods 11, each having a terminal eye 12 swivelled in an opposite pair of ears 10 are employed to hold the arcuate rails together, the free ends of said tie rods being provided with hooks 13 which are engaged with the other pair of ears 10 near the other ends of the rails, and the said rods may be easily and quickly disengaged to permit the rails to be carried separately and placed in position with ease.

In order to align the arcuate track section with the slide rails 4, each curved rail 9 is provided at each end with a socket member 14 formed preferably of heavy sheet metal and formed to accord with the shape of the rails in cross section, as shown in Figure 3. These couplings or sockets 14 are welded, riveted or otherwise secured to the ends of the rails 9 and extend substantially half their lengths beyond the ends of the rails and are similar in all respects to the sleeves or couplings shown in the above-mentioned patent, except that they are permanently attached to and are carried by the rails 9.

The couplings or sockets 14 thus permit the arcuate rails to be applied to the ends of the slide rails in a manner to provide a turn either to the right or the left, depending upon which end is placed in alignment. The couplings are each provided with a bent portion 15 to engage the base flange portions of the arcuate rails and are also provided with a bent portion 16 to engage the ball portions of the rails 9, so that a rigid connection is afforded between the slide rails and the arcuate track section.

Each coupling is provided on its inner

face with an ear 17, and those ears carried by the couplings of the outer rail member have swivelled thereto a tie rod 18 by means of an eye 19, while the other ends of said rods are provided with hooks 20 for detachable engagement with the ears 17 of the inner rail member 9, said rods being for the purpose of locking the end portions of the two rails in proper spaced relation. All of the tie rods may be held in their locked positions by means of cotter keys if desired, and it will be seen that the wheels of the mine car may easily roll off the ends of the permanent track onto the balls of the angularly disposed slide rails and thence, over the relatively thin couplings, onto the arcuate track section to bring the car close to the right hand or the left hand side wall of a runway, as desired, and, as the door or passageway is extended through said wall, either straight or curved rail sections may be added thereto as necessary.

From the foregoing it will be seen that a simple, cheap and strong and durable curved track section has been provided for use in connection with the slide rails of mine tracks and that the same may be easily handled and quickly placed in position for either a right or a left hand turn.

What is claimed is:—

1. A curved track section for extending the ends of slide rails to one side comprising inner and outer arcuately-bent rails of ordinary construction, said arcuate rails being adapted to rest on their sides upon ties, the base flange of the inner, shorter curved rail being on the outside thereof while the base flange of the outer, longer curved rail is on the inside thereof to accord and align with the ends of the similarly positioned slide rails, sockets carried by the ends of the curved rails to receive the ends of said slide rails, intermediate tie rods terminally pivoted at one end to one of the curved rails and detachably connected at the other ends to the other curved rail, and tie rods hinged at one end to one of the sockets and detachably connected to the opposite socket at each end of the curved rails, said tie rods acting to hold the latter in parallelism.

2. A curved track section for coaction with slide rails of mine tracks comprising an inner and an outer arcuate rail concentric to each other and each resting sidewise upon ties or supports, the base flanges of the two rails being opposite each other, inwardly directed ears secured to said base flanges, intermediate the ends of the rails, tie rods each swivelled at one end to one of an opposite pair of ears and having hooks at their free ends for connection with an opposite ear near the other end of the rails, said tie rods being crossed, metal sockets formed on the ends of the arcuate rails to receive the ends of the slide rails and hold the curved

track section in alignment therewith, ears secured to the inner opposed faces of the sockets, radially disposed tie rods terminally swivelled to one of the latter ears at each 5 end of the section and having a hook for engagement with the opposite ear to hold the ends of the rails together, all of said tie rods

being detachable at one end to permit separate handling of the arcuate rails.

In testimony that I claim the foregoing 10 as my own, I have hereto affixed my signature.

JAMES EDWARD WILSON.
